SAFETY RAZOR BLADE SHARPENER

Filed Feb. 3, 1932

By Cameron, Kerkam & Leetton
Attorneys

UNITED STATES PATENT OFFICE

HARLEY A. COY, OF MASCOT, TENNESSEE

SAFETY RAZOR BLADE SHARPENER

Application filed February 3, 1932. Serial No. 590,744.

This invention relates to a stropping or honing device for safety razors, more particularly for safety razors of types now in general use.

5 One of the objects of the invention is to provide a novel stropping or honing device for a safety razor which device is small, light, inexpensive and efficient.

Another object is to provide a novel stropping or honing device which can be assembled with safety razors of types now in use without interfering with the use of the razor for shaving and which can be used for sharpening the blade without removing either the 15 device or the blade from the razor.

Another object is to provide a novel stropping or honing device for a safety razor which can be sold or marketed apart from the razor itself as a separate device or attachment to 20 be applied to and used with razors of types now known and in general use.

Two embodiments of the invention have been illustrated in the accompanying drawing, but it is to be expressly understood that 25 said drawing is for purposes of illustration only and is not to be construed as a definition of the limits of the invention, reference being had to the appended claims for this purpose.

30 In the drawing,

Fig. 1 is a perspective view of a razor having attached thereto a sharpening device embodying the invention;

Fig. 2 is a sectional view of the razor taken 35 on line 2-2 of Fig. 1;

Fig. 3 is a view similar to Fig. 2 but showing the sharpening device ready for use;

Fig. 4 is a sectional view of the razor taken on the line 4-4 of Fig. 1;

40 Fig. 5 is a perspective view of the sharpening device; and

Fig. 6 is a perspective view of a device embodying the invention and adapted for use with a somewhat different type of razor.

45 Referring now to the drawing, Figs. 1 to 4 inclusive illustrate a conventional razor of a type well known and in general use. This razor includes a top clamping member 1 having secured to its central portion a depending threaded stem 2 and a depending longitudi-

nally extending bar 3. In this type of razor, the bar 3 normally engages in a slot 4 in a blade 5, and the stem 2 passes through a central opening in said blade and through a central opening in a guard or bottom clamping member 6 provided with serrated guards 7. The clamping members 1 and 6 and the blade 5 are secured together by threading the usual handle 8 onto the threaded stem 2 whereby the blade 5 is firmly clamped between said clamping members, the bar 3 normally engaging in a slot 9 formed in the bottom clamping member 6. As shown in Fig. 4, the bar 3 and slot 9 do not extend the entire length of the clamping members 1 and 6. 55 Moreover, the top clamping member 1 is provided at its four corners with projecting lugs 10, the corners of the blade being cut out to receive these lugs. It will be understood however that the razor as thus far described is of conventional form and is shown for purposes of illustration only.

It is known that the edge of a blade in a razor of this type tends to be turned over away from the guard 7 and toward the top clamping member 1 when the razor is used and hence the blade should first be sharpened on the side adjacent the top clamping member 1. In conformity with the present invention, a stropping device is provided which can be 60 assembled with the razor between the blade and the top clamping member and which is capable of lateral displacement at right angles to the blade edges so as to strop or hone the blade. Fig. 5 shows a device embodying the 65 invention which is adapted for use in a razor of the type described above. This device comprises a substantially rectangular frame indicated generally at 11 and having its central portion cut out as shown at 12, the length 70 of the cut out portion 12 being sufficient to receive the bar 3 and the width of the cut out portion 12 being sufficient to permit lateral displacement of the stropping device of the desired extent. The frame 11 can be molded 75 from hard rubber, or stamped, molded or assembled from any suitable material or combination of materials such as metals, alloys and the like, provided only that the undersurfaces 80 of the sides 13 of the frame provide suitable 85

stropping or honing surfaces for the edges of the blade. If desired, the stropping or honing surfaces may be of different material from the remainder of the device and may be secured to the rectangular frame 11 in any suitable manner, but usually the entire device will be formed of a material which of itself provides the desired honing or stropping surfaces.

This device is shown assembled with a razor in Figs. 1 to 4 inclusive, being positioned between the blade 5 and the top clamping member 1. In Figs. 1 and 2, the razor is in condition for shaving and in this position the upper surfaces of the sides 13 of the stropping device are engaged by the lugs 10 of the top clamping member to hold and flex the blade, flexibility being provided if necessary at 14 in the end portions of the frame. As clearly shown in Figs. 2 and 4, the bar 3 fits within the cut out portion 12 of the device, and according to the thickness of the device said bar may extend into the slot 4 in the blade or further into the slot 9 of the guard 6, although for reasons pointed out below the blade is securely held against turning regardless of the bar and slot.

The frame is provided at its ends with knobs 15 which as shown in Figs. 1 and 4 lie outside of the ends of the razor clamping members, and said knobs are provided with downwardly extending flanges 16 which engage the ends of the blade and also the ends of the guard member 6. These flanges 16 provide guides which insure that the lateral movement of the stropping device shall take place in a direction at right angles to the blade edge; moreover, the blade and clamping member are held against turning by the stem 2 and by the knobs 15 and their flanges 16, both during stropping and when the razor is in use for shaving.

When it is desired to use the stropping device, the tension on the blade 5 is released by unscrewing the handle 8 until the parts are in the position shown in Fig. 3. The blade 5 in returning to normal unflexed condition lifts the top clamping member 1, and may in some cases remove the bar 3 from engagement in the slots 4 and 9, depending on the extent of the bar and the thickness of the stropping device. However, in any event the blade is held against turning in the razor and against lateral movement by virtue of the threaded stem 2 and the flanges 16 as described above. The knobs 15 are now grasped between the fingers of one hand and the handle 8 is moved back and forth with the other hand, causing the razor together with the blade to reciprocate relative to the stropping device and the stropping surfaces to pass over the blade edges. For more thorough sharpening, the blade can be reversed in the frame and the operation repeated.

Fig. 6 shows another device embodying the

invention which is adapted for use with a different type of razor. In this figure the stropping device comprises a curved plate 17 provided with a plurality of transversely elongated openings 18. The top clamping member 19 (shown in dotted lines) is provided with three posts 20, the center post being threaded to receive the usual handle. It will be understood that this top clamping member is used with the usual blade and bottom clamping member each having three openings through which the posts 20 extend. The device 17 is provided with knobs 21 having depending flanges 22 which engage the ends of the blade and of the bottom clamping member for guiding the stropping device. With this type of razor, the blade is always held against turning and against lateral movement by the three posts 20 which pass through the holes formed in the blade. The stropping device however, is capable of lateral movement since the posts 20 pass through the elongated openings 18. By loosening the handle, grasping the knobs 21 in the fingers of one hand, and moving the razor handle back and forth with the other hand, the same stropping action is obtained as described above in connection with Figs. 1 to 5, inclusive.

It will be seen that devices embodying the invention may be manufactured and sold separately and apart from the complete razor and that they are designed as attachments to be used with razors of types now on the market and widely used. The device is inexpensive, small and light in weight, and efficient in operation. Preferably the device is assembled with the razor as shown in the drawing and is therefore always in position for sharpening and ready for use, although there is no interference with the normal operation of the razor. It is only necessary to loosen the handle slightly in order to sharpen the blade and this can be accomplished without removing either the blade or the sharpener from the razor.

While only two embodiments of the invention have been described and illustrated in the drawing, it will be understood that the invention is capable of various other physical embodiments and that changes may be made in the form, details of construction and arrangement of the parts without departing from the spirit of the invention. Moreover, it will be understood that devices embodying the invention are not restricted to use with razors of the two types described above but may be adapted to other types as well. Reference is therefore to be had to the appended claims for a definition of the limits of the invention.

What is claimed is:

1. In a razor, a guard, a clamping member, a blade between said guard and clamping member, means for holding said member,

blade and guard in assembled relation, and a sharpening device mounted between the blade and clamping member for transverse movement relative to the blade and clamping member.

2. In a razor, the combination of a guard, a clamping member, a blade between said guard and clamping member, means for holding said clamping member, blade and guard in assembled relation, a sharpening device mounted between said blade and clamping member for transverse movement relative to the blade, and knobs on the ends of said sharpening device and extending beyond the ends of the razor.

3. In a razor, the combination of a guard, a clamping member, a blade between said guard and clamping member, means on said clamping member extending through said blade and engaging said guard for holding said clamping member, blade and guard in assembled relation, and a sharpening device mounted between said blade and clamping member, said sharpening device having a transversely elongated opening through which said means extends, whereby said sharpening device is capable of transverse movement relative to said blade.

4. A sharpening device for use with a razor of the type comprising a guard, a clamping member, a blade and means extending from said clamping member through said blade and engaging said guard for holding the same in assembled relation, said device comprising a frame adapted to be mounted between the blade and clamping member and having sharpening surfaces, said device having a transversely elongated opening of greater transverse extent than said means whereby the device is capable of transverse movement relative to the blade.

5. A sharpening device for use with a razor of the type comprising a guard, a clamping member, a blade and means extending from said clamping member through said blade and engaging said guard for holding the same in assembled relation, said device comprising a frame adapted to be mounted between the blade and clamping member and having sharpening surfaces, said device having a transversely elongated opening of greater transverse extent than said means whereby the device is capable of transverse movement relative to the blade, the ends of said device being adapted to project beyond the ends of the razor and being provided with gripping knobs.

6. In a razor, the combination of a guard, a clamping member, a blade between said guard and clamping member, means secured to said clamping member and extending through said blade into engagement with said guard for preventing relative movement between the parts, a sharpening device mounted between the blade and clamping member

and having a transversely elongated opening through which said means extends, the ends of said sharpening device extending beyond the ends of the razor and being provided with flanges engaging the ends of the blade and 70 razor parts for guiding the transverse movement of the device.

7. A sharpening device for safety razors comprising a substantially rectangular member having sharpening surfaces adjacent its sides and having a transversely elongated opening, said device being provided at its ends with gripping knobs.

8. A sharpening device for safety razors comprising a substantially rectangular member having sharpening surfaces adjacent its sides and gripping knobs at its ends, the central portion of said device being removed to form a substantially rectangular opening 80 therethrough.

9. A sharpening device for safety razors comprising a substantially rectangular member having sharpening surfaces adjacent its sides and gripping knobs at its ends, said device being provided with a plurality of transversely elongated openings therethrough.

In testimony whereof I have signed this specification.
